UNITED STATES PATENT OFFICE.

ORRIN BAILEY, OF ELIZABETH, NEW JERSEY, ASSIGNOR TO EMIL BLOCH, OF NEW YORK, N. Y.

DRESS-FASTENER.

1,198,813.

Specification of Letters Patent. Patented Sept. 19, 1916.

Application filed February 9, 1915. Serial No. 6,989.

To all whom it may concern:

Be it known that I, ORRIN BAILEY, citizen of the United States, and resident of 58 Summit road, Elizabeth, in the county of 5 Union and State of New Jersey, have invented certain new and useful Improvements in Dress-Fasteners, of which the following is a specification.

My invention relates to dress fasteners 10 and has particular reference to an improved construction of the said fasteners.

As is well known dress fasteners are composed of two members, one of which members is attached to a certain portion of a 15 dress or garment while the other member is attached to another portion of the said garment which is to be fastened to the said first portion; the said two members are then pressed together in order to fasten the said 20 portions of the garment together. When so pressed together the two members of the fastener are retained in closed position by means of a spring until the tension of the 25 said spring is overcome by forcing the said parts apart.

My invention aims at providing a socket member for a dress fastener of simple and compact construction, the parts of which easily lend themselves to manufacturing by 30 mechanical means on a large scale. Furthermore, the spring which holds the two members of the fastener in closed relation to each other is of a shape which easily lends itself to manufacture by mechanical means 35 and yet has a greater resiliency than the springs heretofore used, while at the same time it is very much shorter and it is possible therefore, to effect a considerable economy of material. Moreover, by reason of 40 the simple and short form of the spring, the mechanism by which the said spring is formed has a much longer life.

My invention is illustrated in the accompanying drawing.

Figure 1 of the said drawing is a plan view of my socket member for a dress fastener; Fig. 2 is a cross-section of the same, like numbers referring to like parts.

The said socket member is composed of a 50 circular disk of sheet metal 16 usually formed slightly concave, the outside edge of which is spun up at right angles to the said bottom portion, 16, for the purpose of forming a rim 4. The upper extremity of the

said rim is beaded over inwardly. The central part of the said bottom portion is punched upward from below so as to form a hollow boss or projection 2. Near the base of the said projection the latter is provided with two opposite longitudinal slots 60 3, 3. Within the substantially cup-shaped vessel thus formed there is located a spring 5. The said spring has substantially the form of a U, and the extremities 8 thereof are bent outwardly in order to form also 65 two substantially U-shaped end portions. The central U-shaped part 7 of the said spring bears against the said rim 4, and the two U-shaped extremities of the said spring also bear against the rim 4, the spring being held in position within the said cup-shaped vessel by means of the beaded over rim thereof. The straight portions of the said U-shaped springs pass within the said slots 3, 3, so that they partially protrude 75 into the interior of the said hollow boss or projection 2. In order to be able to sew the said socket member to a garment, it is provided with four circular holes 9.

I do not desire to limit myself to the precise form of construction shown in the drawings as it is evident that various modifications may be made therein without departing from the spirit of my invention.

Having thus described my invention I claim:

A socket member for a dress fastener comprising a substantially dish-shaped vessel having a beaded-over rim and a central hollow projection, said projection being 90 provided with two oppositely-disposed slots and a substantially U-shaped spring having the ends thereof reversely bent outward, the U-shaped part of the spring consisting of two portions substantially parallel to each 95 other throughout their whole lengths, the said parallel portions being partially disposed in the said slots, the apex of the U and the extremities of the outwardly-bent ends resting against the beaded-over rim of the said dish-shaped vessel.

Signed at New York, in the county of New York, and State of New York, this 8th day of February, A. D. 1915.

ORRIN BAILEY.
